ATTORNEYS

UNITED STATES PATENT OFFICE

HARRISON R. WILLIAMS, OF NEW YORK, N. Y.

VENDING MACHINE

Application filed February 19, 1929. Serial No. 341,236.

My invention relates to dispensing or vending machines, preferably of the coin-controlled type, for selling packaged goods or other articles, its leading aim and purpose being to provide a construction of this character which will dispense or deliver the goods with accuracy, reliability and certainty, as the appliance is operated from time to time incident to the deposit of coins therein.

10 Other objects and purposes of the invention will be made apparent to those skilled in this art by means of the following detailed description of a desirable and preferred embodiment thereof, which is to be read in connection with the accompanying sheets of drawings illustrating such incorporation of the invention in physical form, and throughout the several views of which like reference characters have been employed to designate 20 the same structural parts.

In these drawings,—

Fig. 1 is a substantially central, vertical cross-section through the appliance;

Fig. 2 is an enlarged, vertical cross-section through the lower portion only of the structure, that is to say, through a side extension on the lower part of the casing;

Fig. 3 is a vertical section, on a still larger scale, on line 3—3 of Fig. 2, the parts being 30 viewed in the direction indicated by the arrows;

Fig. 4 is a horizontal section on line 4—4 of Fig. 1, the elements being viewed looking downwardly;

Fig. 5 is a view similar to that of Fig. 2, with the movable parts in a different position, that is to say, with the operating handle depressed;

Fig. 6 is a larger vertical section on line 40 6—6 of Fig. 2, the arrows indicating the direction from which the view is taken; and

Fig. 7 is a fragmentary, enlarged section on line 7—7 of Fig. 2.

By reference to the plurality of views of 45 these drawings, it will be perceived that the novel and improved dispensing or vending machine includes an upright casing or housing 21, comprising a back wall 22, to which the combined top, front, bottom and end walls 23, 24, 25 and 26, respectively, are

hinged at 27, so that the front part of the casing may be swung down, giving access to its interior for replenishing purposes.

These casing or housing members are held in closed position by means of a key-operated latch 28 disengageably co-operating with a fixed catch 29 extended forwardly from the back wall, as shown in Fig. 5.

The front wall of the housing or casing has a glass-covered window 31 (see Fig. 1) and 60 a dispensing or discharge opening 32 through which the packages 33 or other goods, as the case may be, are delivered to the purchaser.

Internally, on the end walls 26, I provide 65 registering, vertically-disposed guides or rails 34, and near the lower part of such housing a pair of appropriately-jounaled, front and rear, longitudinally-recessed shafts 35 and 36 are employed in the relation illustrated.

A lower, notched separator-plate 37 is supported by such companion or correlated shafts by reason of its front and rear marginal portions occupying the registering recesses or cavities of the two shafts (Fig. 1), 75 such lowermost plate 37 supporting above it an alternating series or stack of such plates 37 and the packages of goods 33 to be sold by the machine.

These plates are notched at their ends at 80 38 to receive and be guided by the vertical rails or bars 34, and they are also cut away at the two points 39, 39, at their front edges, and at 41 at their rear margins, in order that they may escape conflict, when released by the simultaneous rocking of the two shafts 35 and 36, with a back, inclined lug 42 mounted on the inner side of the rear casing wall, and with a pair of similarly-inclined, spaced fingers 43, 43, located on the back of the front wall of the housing, these three supports 42 and 43 being so located and sloped that when a package is deposited or dropped on them, it will slide down by gravity out through the delivery aperture 32.

To assure that the pile or stack of packages and separator-plates shall have sufficient weight at all times for their proper descent, a weight 44 is placed on the uppermost package, and it is guided by the rails 34, as are the

plates, such weight having an upstanding, front flange 45 carrying a plate 46 designed to display the word "Empty" when it comes opposite the window 31, whereby it may be read from the outside and inform the intending purchaser not to deposit a coin, as no delivery of a package can then be effected.

From the above description, it will be understood that every time the companion shafts are rocked simultaneously in opposite directions, the lowermost plate and the first package resting thereon will be released and fall, those above them being temporarily held from descent by reason of the unrecessed parts of the shafts turning in under the lowermost supporting-plate.

The freed or released plate falls down to the bottom of the casing or housing, passing by the inwardly-projecting lugs or fingers 42 and 43, by reason of its registering notches 41 and 39, respectively, but the disengaged package, which has no such notches, is deposited or drops on to the sloping fingers, down which it slides by gravity, out forwardly, through the opening 32, to the purchaser.

Just as soon as the two shafts are rocked back to normal or original position, bringing their recesses again into alignment with the supported stack, the latter descends until the lowermost plate falls into the recesses and is supported by the shafts, it, of course, supporting all of the other plates and packages above it.

The actuating mechanism for such shafts and the means for receiving the coins are located in a side extension 47 of the casing, access to the coins in which may be had through a lock-equipped, removable door 48 (Fig. 6), the structural details of which, so far as this invention is concerned, being of no substantial importance.

At their ends, the two shafts 35 and 36 are fitted with inwardly-directed arms 51 and 52, respectively, fixed thereto, and by which the shafts may be rocked in their bearings to perform their specified functions, the free ends of such arms being connected by links 53 and 54 to a vertically-slidable frame 55 pulled upwardly by an appropriate coiled spring 56 connected thereto and to a pin 57 on the casing wall, such frame being guided in its vertical reciprocations by an extension 58 depending therefrom and slidable between a pair of guide lugs 59, 59, forming part of, or attached to, the casing, the upward travel of the frame, and hence the rocking or turning movements of the shafts, being limited by nuts 61 on the threaded end of the part 58 striking against the under surfaces of the lugs of projections 59.

The upper part of this vertically-reciprocatory frame is guided in its travel by lugs 62, 62, on the casing, and by a guide rib 63 on the opposite wall of the casing.

A right-angle guiding-tube 64, open at its top end, which extends through the upper wall of the casing extension 47 for the reception of the coins, delivers the received coin 65 into the frame-aperture or open space, as shown in Figs. 2, 5 and 6, beneath a pair of spaced fingers 66 extended laterally into the frame-opening from the top portion of the side of a lever 67 fulcrumed on the casing wall at 68, extending forwardly through a casing-hole 69, the protruding part of the lever forming an operating handle 71, and provided with a lifting spring 72 which tends to rock the lever upwardly.

Thus the coin forms an operative mechanical connection between the lever and the pair of shafts 35 and 36 which support the stack or stock of packages, through the frame and the other mechanical elements heretofore described.

In order that the lever when depressed may slide the frame downwardly to turn these two shafts to release a separator-plate and one of the packages in the manner described, the coin must be prevented from tipping over, and accordingly the lever has an enlargement 73 against which the coin may bear sidewise, and which prevents the coin from falling out of the frame at one side.

To preclude such coin from falling out of the frame in the other or opposite direction and to hold it pressed in upright position against the part 73 of the lever, a vertically-disposed, pivoted, spring-pressed finger 74, with a beveled lower end, is employed, such finger being hinged at 75 on a shaft rockingly mounted in spaced bearings 76, 76.

During the upward stroke of the frame, after it has been depressed to effect a package delivery, the finger, under the action of its spring, having swung toward the lever as soon as the coin went down beyond the finger, the latter, by reason of its sharp lower end, becomes interposed between the lever and the coin and tips the latter over out of the frame, from which it falls into the lower part of the casing.

To facilitate this action, the face of the lever toward the coin may be somewhat beveled or inclined, as is fully shown in Fig. 6.

In order to insure a full stroke of the lever and frame and to hold the finger 74 normally away from the face of the lever sufficiently to permit the entrance of the coin therebetween, the following coacting instrumentalities have been provided.

A spring 77 is fastened at its lower end to the casing at 78, such member 77 having a turned-over or hook end 79 at its top and a cam member 80 intermediate its length.

The frame has a projection 81 designed to co-operate with such cam, and a lug 82 arranged to coact with a rod 83 projecting from the side of the finger 74.

Assuming that the intending purchaser has

deposited the coin in the chute 64 and that such coin has rolled down into place between the lever lugs 66 and the frame 55, as shown in Fig. 2, where it constitutes an operative 5 mechanical connection between such movable elements, the coin being between the side of the lever and the finger 74, the latter being held spaced away from the lever by the action of lug 82 on the lateral finger arm or rod 83, the operator presses down on the handle 71 and rocks the lever in the same direction.

10 The corresponding movement of the frame, occasioned by such swinging of the lever, through the intervening coin, turns the two 15 shafts 35 and 36 and causes the discharge of one package and its delivery to the purchaser.

As soon as the frame partakes of such depression, its lug 81 leaves the cam element 80, and the spring flexes toward the lever and 20 frame to carry its hook 79 above the lever so that the latter cannot rock up to its initial position until the hook has been pressed back out of the way.

25 The descent of the frame lowers projection 82 away from the finger-rod 83, and hence the finger 74 is free to respond to the action of its spring, and it presses against the adjacent face of the coin and keeps the latter in place.

30 When, however, the frame reaches its lowermost position, the coin has been carried below the sharp, lower end of such spring-actuated finger 74, and the latter rocks over further, so that when the purchaser initiates 35 the release of the lever, it moves up part way, the frame traveling likewise, and as the frame thus ascends, the finger 74 wedges the coin out of the same, so that it falls into the bottom of the casing.

40 As soon as this occurs, the spring 56 quickly elevates the frame to original position, and during this travel its lug 81 engages the cam 80 and forces the spring 77 back, carrying the hook 79 out of the path of travel of 45 the lever, whereby the latter may ascend, under the action of its spring, to its original position.

When the frame reaches its uppermost position, the parts 82 and 83 will retract the 50 finger 74 into its initial position, by reason of the coaction of the parts 82 and 83, so that the next coin introduced may properly roll into place in the frame between the lever and the finger.

55 If for any reason the coin is not thus ejected from the frame, which, of course, is unlikely, the frame cannot ascend to its original height, and therefore the lock or catch 79 will not be retracted, it being understood 60 that the parts 77, 80, 81, and 79 constitute a safety mechanism to prevent the operation of the appliance if the coin has not been properly discharged into the casing.

It is desirable that means be provided to 65 prevent the introduction or insertion of a

coin if the supply of packages, to be sold, in the casing has become exhausted, and accordingly the weight 44 is provided with a spring-actuated plunger 84 fitted or supplied with a handle 85, the end of such plunger 70 normally riding on the inner surface of that wall of the casing adjacent to the coin-tube 64, the upper end of which, just below its mouth 86, has registering holes 87, 87, which are in alinement with another hole 88 75 through the adjacent casing-wall, this series of holes being in register with the position of the rod 84 when the weight 44 is in its lowermost position corresponding to the empty condition of the appliance. 80

It will be readily understood, therefore, that when the vending machine has no more packages to sell, and requires replenishing, the rod 84 will be automatically projected through the coin-chute, as illustrated in Fig. 85 3, thus preventing the introduction of a coin which could not result in the sale of one of the packages.

When the supply of goods or packages in the casing has become exhausted and is to be 90 replenished, the accumulated supporting plates in the bottom of the casing are removed and are inserted between the plurality of packages or articles, so that the replenished 95 stack in the casing will present the general appearance of alternating plates and packages, as depicted in Fig. 1, which, however, shows the stack or supply almost exhausted.

Those acquainted with this art will have 100 no difficulty in understanding the substantial and material benefits and advantages which accrue from the employment of a mechanism incorporating the above-specified structural characteristics; but it is to be remembered that the invention is not limited 105 and restricted to the precise and exact details illustrated and described, because these can be modified within comparatively wide limits without departure from the heart and essence of the invention as defined by the appended claims. 110

I claim:

1. In a vending machine, comprising a casing, and movable means in said casing to support a stack of articles to be dispensed, 115 the combination of coin controlled means to actuate said movable means to deliver said articles one at a time, including a manually-operated lever, a coin chute and operating means connected to said movable means, said chute delivering the coin to form an operative mechanical connection between said lever and operating means, and a finger to hold said coin in correct operative position until the article has been released from the stack, means for moving said finger to accomplish the ejection of said coin, and means independent of said coin to move said finger out of its ejecting position. 120

2. In a vending machine, comprising a cas- 130

ing, movable means in said casing to support a stack of articles to be dispensed, the combination of coin controlled means to actuate said movable means to deliver said articles one at a time, including a manually-operated lever, a coin chute and operating means connected to said movable means, said chute delivering the coin to form an operative mechanical connection between said lever and operating means, means to hold said coin in correct operative position until the article has been released from the stack, said means acting positively to remove the coin from said operative connecting relation after the article has been released from the stack, and means to prevent the lever from returning to initial position provided the operative connection through said coin is not broken.

3. In a vending machine, comprising a casing, movable means in said casing to support a stack of articles to be dispensed, the combination of coin controlled means to actuate said movable means to deliver said articles one at a time, including a manually-operated lever, a coin chute and operating means connected to said movable means, said chute delivering the coin to form an operative mechanical connection between said lever and operating means, said lever including a coin receiving pocket extending around one face and a portion of the lower edge of the coin, a finger holding said coin against the wall of the pocket until the article has been released from the stack, and means for causing said retaining finger to eject said coin after the article has been released from the stack.

4. In a vending machine, comprising a casing, movable means in said casing to support a stack of articles to be dispensed, the combination of coin controlled means to actuate said movable means to deliver said articles one at a time, including a manually-operated lever, a coin chute and operating means connected to said movable means, said chute delivering the coin to form an operative mechanical connection between said lever and operating means, said lever including a coin receiving pocket extending around one face and a portion of the lower edge of the coin, a finger holding said coin against the wall of the pocket until the article has been released from the stack, means for causing said retaining finger to eject said coin after the article has been released from the stack, and means for causing said finger to stand away from said wall of said pocket to allow the coin to be received therein.

In testimony whereof I have affixed my signature to this specification.

HARRISON R. WILLIAMS.
